DELAWARE

RIVET SETTING MACHINE

Application filed April 5, 1930. Serial No. 441,999.

This invention relates to riveting machines and more particularly to machines setting small hollow rivets or eyelets.

One of the objects of the present invention is to adapt a rivet setting machine for automatic operation upon a piece of work requiring a plurality of rivets or eyelets. Accordingly, the present invention provides a work holder and means for intermittently moving the work holder so as to bring the rivet receiving apertures of the work successively in alignment with the rivet setting mechanism. The present invention provides the means for automatically stopping the machine when all the rivets have been applied to the work piece.

A further object of the invention is to provide a conveyor carrying a plurality of work holders, one of which may be in the position for receiving the operations of a riveting machine, and the other of which may be in a position for unloading and reloading the work, the mechanism for moving the work holders being common to all of the work holders of the conveyor.

Further objects and advantages of the present invention will be apparent from the following description, reference being had to the accompanying drawings wherein a preferred embodiment of one form of the present invention is clearly shown.

In the drawings:

Fig. 1 is a perspective side view of a machine embodying the present invention.

Fig. 2 is a fragmentary end view looking in the direction of arrow 2 of Fig. 1.

Fig. 2a is a sectional view on line 2a—2a of Fig. 2.

Figs. 3 and 3a are sectional views on the line 3—3 of Fig. 2 and are drawn to a larger scale. Fig. 3 shows the rivet feed in position for locating a rivet in alignment with the riveting punch pilot. Fig. 3a shows the rivet feed retracted from the pilot.

Fig. 4 is a fragmentary perspective view of the part of the machine shown in Fig. 1.

Fig. 5 is a plan view of a work piece having a rivet or eyelet attached thereto.

Fig. 6 is a fragmentary side elevation showing a fragment of the work holder with the work piece attached thereto. The work piece

is shown in longitudinal section and an eyelet shown in longitudinal section is fastened to one of its apertures. Fig. 6 shows a fragment of a riveting punch pilot for applying a rivet to another aperture of the work piece, and shows a fragment of a riveting punch for fastening the rivet in place.

Fig. 7 is a fragmentary longitudinal view of the work holder, work piece, rivet, rivet pilot and rivet punch in position just prior to up-setting the lower end of the rivet.

Fig. 8 is a fragmentary side elevation of the machine looking in the direction of the arrow 8 in Fig. 2.

Fig. 9 is a fragmentary side elevation of a portion of the machine shown in Fig. 8 and is drawn to a larger scale. The rivet and rivet feed shown in this figure are shown in longitudinal section.

Fig. 10 is a fragmentary sectional view on the line 10—10 of Fig. 8.

Fig. 11 is a fragmentary sectional view on the line 11—11 of Fig. 10.

Fig. 12 is a fragmentary sectional view on the line 12—12 of Fig. 11.

Fig. 13 is a fragmentary longitudinal sectional view of one of the work holders.

Fig. 14 is a fragmentary sectional view on the line 14—14 of Fig. 10.

Fig. 15 is a sectional view on line 15—15 of Fig. 14.

Fig. 16 is a sectional view on the line 16—16 of Fig. 8.

Figs. 17 and 18 are fragmentary sectional views taken on the lines 17—17 of Fig. 14 and show the clutch in disconnected and connected position.

Referring to Fig. 1 the machine comprises a pedestal 20 supporting the table bracket 21 supporting a frame 22. Frame 22 supports a main operating shaft 23 carrying at its left hand end as viewed in Fig. 8 or front end as viewed in Fig. 2 a crank pin 24 cooperating with a Scotch yoke 25 provided by a vertical slide 26, the lower end of which carries a punch 27. As shown in Fig. 7, punch 27 is tubular and supports a pilot 28 adapted to move downwardly into a rivet A when located vertically below the pilot. The pilot 28 is yieldingly urged downwardly by spring 30.

29 housed within the punch 27, downward movement being limited by the head 30 of the pilot 28 striking the lower wall 31 of the recess which receives the head 30 and 5 spring 29.

10 The disclosed embodiment of the present invention comprises a rivet setting machine which is adapted to apply tubular rivets or eyelets to the work piece B, which is a non-conducting cylindrical body provided with a circular row of three holes B¹, each hole having the part B² adjacent one end of the body B and of smaller diameter than the major portion B³ of the hole. This smaller 15 portion B² of smaller diameter is adapted to receive the rivet A which is attached to the body as shown at A¹ in Fig. 6. The body B is mounted on a work holder 40 having posts or anvils 41 each received by one of the holes 20 B¹ when the body is placed on the work holder. The post 41 is slightly less in diameter than the hole portion B³ and this diameter terminates at 42 which is slightly below the shoulder portion B⁴ connecting the 25 cylindrical side walls of the hole portions B² and B³. The post or anvil 41 is provided with a tubular projection 43 of less outside diameter than the hole portion B² and located so as to project slightly up into the hole portion B². The projection 43 joins the main 30 portion of the post 41 by a shoulder having a curved annular surface 44.

35 When one of the posts 41 is vertically below the punch 27, by mechanism to be described, the shaft 23 is rotated to cause the pilot 28 to descend through a rivet A located vertically above it, thereby causing the rivet to move from a position such as shown in Fig. 6 to the position shown in Fig. 7. As the 40 punch 27 moves downwardly, the lower end of the pilot 28 engages the extension 43 of the post 41 whereupon further downward movement of the pilot 28 is arrested. The continued downward movement of the punch 45 45 causes a rivet to be moved into the position shown in Fig. 7 wherein the rivet has been located so as to have its lower end riveted or curled around against the shoulder B⁴ of the body B by riveting operation produced 50 during further downward movement of the punch from the position shown in Fig. 7. It will be noted that the surface 44 of the post 41 operates to cause the lower end of the rivet to be upset against the surface B⁴ of the body B by riveting operation produced 55 shown in connection with the rivet A¹ in Fig. 6. This riveting operation takes place while the flange AF of the rivet A is forced by the punch 27 against the upper surface of the body B. The rivet having been attached to 60 the body, will remain in place as the punch and pilot ascend to a position for engaging another rivet which has automatically been placed in alignment with the pilot by the operation of an automatic rivet feeding device to be described.

65 Referring to Figs. 11 to 13, the work holder 40 is rotatably supported by a work holder conveyor 45 carrying a plurality of such work holders. The conveyor 45 comprises a metallic block pivotally attached by screw 46 to a bracket 47 attached to the table bracket 21 by screws 48, the block 45 is operated by a handle 49. The work holder 40 is attached to a gear 50 which rests upon the upper surface of the block 45. The tubular shank 51 of the work holder 40 is threadedly connected with a screw 52, which is threaded through a nut 53 received by a recess 54 provided by the block 45. The nut 53 limits upward movement of the work holder 40. The work 70 holder 40 is maintained in any of the operating positions by a ball 55 urged upwardly by spring 56, there being as many equally spaced detents in the gear 50 for receiving the ball 55 as there are posts 41. The work 75 holder gears 50 are covered by a plate 56 having apertures 57 through which the posts 41 may project to receive the work.

80 Each work holder gear 50 is adapted to mesh with a driving gear 60 pivoted upon a screw 61 threaded into the table 21. The gear 60 is driven by a ratchet 62 cooperating with a driving pawl 63 pivotally attached by screw 64 with a slide 65. Pawl 63 is urged against the ratchet 62 by a spring 63a. The slide 65 85 is guided for horizontal reciprocating movement by a plate 85 secured to the table 21 by screws 86. A spring 66 urges the slide 65 toward the right as viewed in Fig. 10, said spring being connected by screw 67 with the 90 slide 65 and by screw 68 with the table 21. The right hand end of slide 65 is connected by pin 70 with a lever 71 pivoted upon screw 72 carried by bracket 73 which is attached to the table 21. Lever 71 carries at its upper end a roller 74 which cooperates with a plate cam 75 having a single lobe 76. The cam is mounted on and driven by the shaft 23. During each revolution of shaft 23 which 95 produces one complete oscillation of the riveting punch and rivet carrying pilot, the cam 75 will produce one complete oscillation of the lever 71 and slide 65 in order to effect such movement of the gear 60 and gear 50 as will 100 cause the work holder to be rotated at angular distance equal to the angular spacing of the posts 41. The drawings illustrate a work piece having three equally spaced rivet receiving holes, hence, the gear 51 must be rotated 120 degrees. The gear ratio between 105 gears 60 and gears 50 is two to one, hence, the gear 60 is required to be rotated intermittently 60 degrees. In the normal position of gear 60 shown in Fig. 10, the gear is locked against movement by a locking pawl 80 having a point 81 adapted to be received by a gear toothed space and having a tail 82 adapted to be received by shoulder 83 in the slide 65. When the slide 65 moves toward the left in 110 Fig. 10 in order to move the pawl 63 against 115

120

125

130

the ratchet 62, the shoulder 83 of the slide 65 moves away from the tail 82 in order to permit a spring 84 to move the pawl 80 out of locking engagement with the gear 60. This locking feature is desirable since it locks the gear 60 against rotation when moving the conveyor plate 45 in order to bring either of the work holders into operating position in which position the gear 50 of the work holder will mesh with the gear 60. The work holder conveyor is yieldingly held in either of its positions by a ball 87 retained by base 21 and urged by a spring 88 into either of two recesses 89 and 89a provided by the block 45.

15 The shaft 23 is connectible by a clutch to be described with a driving pulley 90 (see Figs. 8, 10 and 14) which is connected by a belt 91 with an electric motor not shown. The pulley 90 carries a bearing liner 92 journaled on the shaft 23. The clutch mechanism comprises a driving pin 93 urged by a spring 94 toward a clutch member 95 attached by a key 96 to shaft 23. The pin 93 is provided with a shoulder 97 cooperating with 20 a latch block 98 guided for radial sliding movement by a notch provided in the hub of the pulley 90 and urged into latching position by spring 99 located between the latch block 98 and a head 100 of a pin 101 attached 25 to the pulley 90. Referring now to Figs. 17 and 18, the pin 93 is adapted to move toward the left into a notch 102 provided by the member 95 and there to engage a wear piece 103. In order that the latch block 98 may be retracted from the pin 93 to permit it to engage the wear piece 103 there is provided a latch release block 104 mounted on an operating rod 105 which passes through bracket arms 106 and 107 and which is yieldingly urged 30 upward into the positions shown in Figs. 14 and 15 by spring 108. The rod 105 is pivotally connected at 109 with a rod 110 attached by a latch block 111 with a rod 112. Referring to Fig. 1 the rod 112 is connected with 35 a lever 113 pivoted at 114 upon the pedestal 20 and having a pin and slot connection 115 with a lever 116 pivoted at 117 and carrying a pedal 118. When the pedal 118 is pressed downwardly the rod 112 will be pressed downwardly thereby causing the latch release block 104 to move the latch block 98 downwardly in order to permit the spring 94 to move the pin 93 into operative engagement with the wear piece 103 of the member 95. 40 When this occurs the pulley 90 will be driv- 45 ingly connected with the shaft 23. If before the end of a revolution of the shaft 23 the pedal 118 be released to permit the rod 112 to move upwardly, the spring 108 will re- 50 turn the block 104 to normal position. In the normal position of the block 104 its bevelled camming surface 120 will be so located that it will be engaged by the left hand end of the pin 93 as it rotates around into contact with 55 the block 104. Thus, the block 104 cooper-

ates to move the pin from clutch engaging position to clutch disengaging position shown in Figs. 18 and 17 respectively. When the pin 93 has been returned to the position shown in Fig. 14, the latch 98 will operate to hold it in this position.

Since a plurality of riveting operations are to be performed upon each work piece, the present invention provides for stopping the machine by disengaging the clutch only after all of these operations have been performed. This is accomplished by providing a pedal holding latch which is automatically rendered operative by depressing the pedal 118 to hold the clutch latch release block 104 in operating position to permit engagement of the clutch. This pedal holding latch comprises the latch block 111 shown in Figs. 14 and 15 and a cooperating pin 130 attached to a horizontally slideable block 131 urged toward the right, as viewed in Fig. 16, by spring 132 attached at one end to the slide 131 and at the other end to a bracket 133 which supports the slide 131. The bracket 133 is attached to the bracket 73. The latch block 111 is guided by bracket 134 attached to the table 21. When the pedal 118 is pressed downwardly to cause the rod 112 to be moved downwardly to permit connecting the clutch, the pedal-latch block 111 will be moved into dotted lines of position 111a shown in Fig. 14, whereupon the pin 130 will be cammed horizontally toward the left and then will snap back over the upper end of block 111 and against the rod 110. Thus the clutch pin 104 will be held in operating position to permit connecting the clutch. The pin 130 is automatically moved to the left just before the machine completes all of its operations upon a work piece by a mechanism comprising a pin 140 adapted to engage the camming surface 141 at the right hand end of the bar 131. The pin 140 is mounted adjacent the periphery of gear 142 journaled on a stub shaft 143 secured to a plate 144 mounted on bracket 73 and a bracket 145 (see Fig. 10). The stub shaft 143 supports a bar 146 which in turn supports a bearing 147 for the right hand of the shaft 23 as viewed in Fig. 14, the gear 142 meshes with a smaller gear 148 driven by the shaft 23. The gear ratio between gears 142 and 148 depends on the number of operations which the machine performs on each work piece. In the illustrated embodiment of the present invention three operations are performed, therefore, the gear ratio between gears 142 and 148 is three to one.

The magazine feed for the eyelets A comprises a frame 150 pivoted at 151 upon the machine frame 22 and carrying a hopper 153 having a cover 154 which is provided with an aperture closed by a lid 155. Through this aperture eyelets are introduced into the hopper 153. The lid is retained closed by a screw 156.

156. Within the hopper there rotates, counterclockwise as viewed in Fig. 2a, an agitator 160 consisting of a plurality of arms of rubber tubing 161 extending from a hub 162 which is connected by a shaft 163 rotatably supported by the frame 150. The shaft 163 carries a pulley 164 driven from a pulley 165 on shaft 166 by a belt 167 which passes around guide wheels 168 and 169. Shaft 166 is supported by a bracket 170 which is supported by frame 22 and by a bracket 171, which shaft 166 is driven by a pulley 172 connected by a belt 173 with a pulley 174 connected with shaft 23.
157. The rotating agitator 160 causes the eyelets A to impinge upon the inner wall of the hopper 153. Some of these eyelets which slide flange downwardly along the base of the hopper leave the hopper through apertures 175 or 176 shaped to permit passage of eyelets flange downwardly only. Such eyelets pass down a chute provided between the edges 177a and 178a respectively of spaced plates 177 and 178 attached to frame 150. These edges are spaced from the frame 150 by an amount exceeding the thickness of the flange of the eyelet A and from each other by an amount less than the diameter of the flange and greater than the diameter of the shank of the eyelet, thus the eyelet flanges hang on the plates 177 and 178 as they slide down the chute provided by these plates.
158. Referring to Figs. 2, 3, 3a, 4 and 9, the plate 177 terminates in a latch 180 which normally operates to retain the lowermost eyelet in the chute. The latch 180 is pivoted at 181 upon a bracket 182 attached to the frame 150 at its lower end. A spring 183 attached to the latch 180 and frame 150 urges the latch 180 toward the plate 178 in order to retain the eyelet A. The frame 150 is caused to oscillate from a position shown in Figs. 2, 3, 8 and 9, in which the lowermost eyelet A will be in vertical alignment with the pilot 28, to a position clockwise from the position shown in Fig. 2 by a cam 190 provided by clutch part 95 shown in Fig. 14. Cam 190 engages a roller 191 pivoted on an arm 192 attached to a rod 193 attached to an arm 194 connected by a link 195 to the frame 150. The rod 193 is rotatably supported by the frame 22 and carries an arm 196, urged counterclockwise by a spring 197 located in a recess in the bracket 171. The spring 197 therefore urges the roller 191 against the cam 190 and the lower end of the frame 150 toward the right, whereas the cam 190 causes the lower end of the frame 150 to move toward the left.
159. In the disclosed embodiment of the invention, the shaft 23 rotates clockwise as viewed in Fig. 2. While the lower end of pilot 28 is moving upwardly above the lower end of frame 150, cam 190 operates to permit the spring 197 to move the lower end of frame 150 toward the right as viewed in Fig. 2 so

that the lowermost eyelet A will be located vertically below the pilot 28. While the pilot 28 is moving downwardly this eyelet A is held in this position until the pilot 28 enters the eyelet; but before the punch 27 touches the latch 180 the cam 190 operates to retract the lower end of the frame 150 from the pilot 28. During this movement of the frame 150 the parts 178, 180, 181 and 183 shown in Fig. 3 move respectively into the positions 178', 180', 181' and 183' shown in Fig. 3a, and latch 180 swings toward the right as viewed in these figures to permit withdrawal of eyelet A. The eyelet A being freed from the magazine feed, the latch 180 snaps back into position for receiving the next eyelet A' which is removed by the pilot 28 from the eyelet feeding device during the next downward movement of the pilot.

160. While the form of embodiment of the present invention as herein disclosed, constitutes a preferred form, it is to be understood that other forms might be adopted, all coming within the scope of the claims which follow.

What is claimed is as follows:

1. Apparatus for setting hollow rivets or eyelets comprising, in combination, a rivet setting punch, a movable work holder for receiving a work piece having a plurality of rivet receiving apertures, said work holder having a plurality of anvils each received by an aperture of the work piece, each anvil cooperating with the rivet punch to set a rivet, means for automatically moving the work holder so that the anvils are located successively in alignment with the punch, and means for feeding the rivets to the work piece apertures. 95

2. Apparatus for setting hollow rivets or eyelets comprising, in combination, a rivet setting punch, a movable work holder for receiving a work piece having a plurality of rivet receiving apertures, said work holder having a plurality of anvils each received by an aperture of the work piece, each anvil cooperating with the rivet punch to set a rivet, means for automatically moving the work holder so that the anvils are located successively in alignment with the punch, and means for feeding the rivets to the work piece apertures. 100

3. Apparatus for setting hollow rivets or eyelets comprising, in combination, a rivet setting punch, a rotatable work holder for receiving a work piece having a plurality of rivet receiving apertures, said work holder having a plurality of anvils each received by an aperture of the work piece, each anvil cooperating with the rivet punch to set a rivet, means for automatically rotating the work holder so that the anvils are located successively in alignment with the punch, and 125

means for feeding the rivets to the work piece apertures.

4. Apparatus for setting hollow rivets or eyelets comprising, in combination, a rivet setting punch, a rotatable work holder for receiving a work piece having a plurality of rivet receiving apertures, said work holder having a plurality of anvils each received by an aperture of the work piece, each anvil cooperating with the rivet punch to set a rivet, means for automatically rotating the work holder so that the anvils are located successively in alignment with the punch, means for automatically stopping the apparatus when all of the work piece apertures have received rivets, and means for feeding the rivets to the work piece apertures.

5. Apparatus for setting hollow rivets or eyelets comprising, in combination, a rivet setting punch, a conveyor, a plurality of work holders each movably supported by the conveyor and each having a plurality of anvils, each received by a rivet receiving aperture of the work piece when placed upon the work holder, each anvil cooperating with the rivet punch to set a rivet, means for moving the conveyor so as to locate a work holder in operating position, means cooperating with any work holder placed in operating position to move said work holder so that the anvils are located successively in alignment with the punch, and means for feeding the rivets to the work piece apertures.

6. Apparatus for setting hollow rivets or eyelets comprising, in combination, a rivet setting punch, a conveyor, a plurality of work holders each movably supported by the conveyor and each having a plurality of anvils, each received by a rivet receiving aperture of the work piece when placed upon the work holder, each anvil cooperating with the rivet punch to set a rivet, means for moving the conveyor so as to locate a work holder in operating position, means cooperating with any work holder placed in operating position to move said work holder so that the anvils are located successively in alignment with the punch, means for automatically stopping the apparatus when all of the work piece apertures have received rivets, and means for feeding the rivets to the work piece apertures.

7. Apparatus for setting hollow rivets or eyelets comprising, in combination, a rivet setting punch, a conveyor, a plurality of work holders each rotatably supported by the conveyor and each having a plurality of anvils each received by a rivet receiving aperture of the work piece when placed upon the work holder, each anvil cooperating with the rivet punch to set a rivet, a gear attached to each work holder, a driving gear with which any work holder gear is adapted to mesh, means for moving the conveyor so as to locate a work holder in operating position and its gear

in mesh with the driving gear, automatic means for intermittently rotating said driving gear and the work holder gear then in mesh with it so that the anvils of said work holder are located successively in alignment with the punch, and means for feeding the rivets to the work piece apertures.

8. Apparatus for setting hollow rivets or eyelets comprising, in combination, a rivet setting punch, a conveyor a plurality of work holders each rotatably supported by the conveyor and each having a plurality of anvils each received by a rivet receiving aperture of the work piece when placed upon the work holder, each anvil cooperating with the rivet punch to set a rivet, a gear attached to each work holder, a driving gear with which any work holder gear is adapted to mesh, means for moving the conveyor so as to locate a work holder in operating position and its gear in mesh with the driving gear, automatic means for intermittently rotating said driving gear and the work holder gear then in mesh with it so that the anvils of said work holder are located successively in alignment with the punch, means for automatically stopping the apparatus when all of the work piece apertures have received rivets, and means for feeding the rivets to the work piece apertures.

In testimony whereof we hereto affix our signatures.

ALVA W. PHELPS.
